UNITED STATES PATENT OFFICE.

GEORGE A. BURNHAM, OF CLIFTONDALE, MASSACHUSETTS, ASSIGNOR, BY MESNE ASSIGNMENTS, TO GENERAL ELECTRIC COMPANY, A CORPORATION OF NEW YORK.

CAM-OPERATED SWITCH.

1,181,733.

Specification of Letters Patent.

Patented May 2, 1916.

Application filed June 23, 1911. Serial No. 635,048.

To all whom it may concern:

Be it known that I, GEORGE A. BURNHAM, a citizen of the United States, residing at Clifftondale, in the county of Essex and 5 State of Massachusetts, have invented certain new and useful Improvements in Cam-Operated Switches, of which the following is a full, clear, and exact specification.

This invention relates to the operating 10 means for electric switches, which switches are adapted for automatic control when desired.

The particular object is to provide a double throw mechanism by the provision 15 of controlling means which is simple in construction and wherein a single device is adapted for successively closing the different parts of the switch.

Another object is to provide operating 20 means of this character which will occupy a minimum space on the switch-board or other support.

The switch is especially adapted for starting electric motors, a movement of the controlling means in one direction throwing the motor in circuit through a compensator, and in the other direction, throwing it directly on the line. In the present instance, a plurality of vertically reciprocating 25 30 movable contacts are provided to engage terminals connecting with the line.

Various other objects and features of my invention will be understood from the following description and accompanying drawings.

Figure 1 is a part sectional view of an oil switch embodying my invention; Fig. 2 is an elevation at right angles to the plane 40 45 of Fig. 1; Fig. 3 is a detailed view of the trip bar partly raised and as seen when looking in the direction of the arrow on Fig. 4; Fig. 4 is a top plan view of the switch, and Fig. 5 is a diagram of the circuit connections.

45 A horizontal supporting plate or bracket 1 is adapted to be mounted on a switch-board panel or other support and supports all parts of the switch and operating mechanism.

50 2 is a galvanized iron oil can removably connected to the support 1 by wing nuts 3, 3^a, etc. An insulating board 4 is secured to the underside of the plate 1 and in which are secured six fiber tubes 5, 5^a, etc., through 55 which are led the terminals which connect

with the line wires. The fixed switch terminals are six L shaped copper bars 6, 6^a, and three plates 7 are supported in the same plane as the bent ends of the bars, to which plates are connected the three lines from the 60 motor. Elastic bridging contacts 8, 8^a, six in number, are secured to two wooden blocks 9, 9^a, the block 9 carrying the three bridging contacts 8 and the block 9^a carrying the three bridging contacts 8^a. These blocks are 65 secured respectively to two metal yokes 10, 10^a, so as to slide up and down in companion yokes 11, 11^a secured to the wooden board 4.

Toggles 12, 12^a each have one link pivoted 70 respectively on cross pins 13 fixed on the yokes 11, 11^a, and the toggles each have the other link pivoted respectively on cross pins 13^a adapted to slide up and down in slots 14 in the fixed yokes 11, 11^a, the pins 13^a being 75 connected respectively to yokes 10, 10^a. Helical compression springs 15, 15^a urge the bridging contacts to open position. The pins 16 forming the knuckle of each toggle coöperate respectively with operating bars 80 17, 17^a, each of the latter being provided with a sloping wall 19 in the end of a circular recess 20. When each bar is moved toward the front of the switch, the lower edge of the bar rides on the pin 16 until the pin alines with the recess 20, when the bar drops over the pin and the wall 21 engages the pin. A movement in the reverse direction will then straighten the toggle and close the switch when the toggle will be set 85 in the line of or slightly over the center, as indicated in the dotted position in Fig. 2. In this position the end of the operating bar 17 extends over a trip piece 22 secured to a pivoted bar 23, the rear end of which lies in the upward path of the plunger of 90 the trip magnet 24.

The forward end of each trip bar 17, 17^a is pivoted respectively in a rocking yoke 25 on a lateral extension of which is pivoted 100 a roller 27. The bar 17^a is shorter than the bar 17 as shown in Fig. 4 and is not adapted for automatic tripping. Either bar may be separately moved forward by a cam 28 formed as an oblique section of a cylinder pivoted on a stud 29, the axis of which is half-way between the two yokes 11, 11^a. When the cam is turned upon the stud 29 to the right in Fig. 1, the inclined face of 105 the right hand half of the cam engages one 110

of the rollers 27 and forces it, together with bar 17, toward the rear of the switch. The notch 20 of bar 17 being in engagement with pin 16, the co-operating toggle is straightened or carried slightly beyond its dead center position. This action closes the corresponding switch contacts 8^a and the toggle holds the same in closed position. In the same way, when the cam is turned to the left from the position shown in Fig. 1, the same action of the other parts takes place in closing contacts 8, the other half of the inclined face of the cam 28 in this case engaging roller 27 of the bar 17^a.

An operating handle 30 is fixed to the cam 28. The operating handle is hollow and contains a spring pressed finger piece 31 and a hook 32 which latter engages with a latch 33 pivoted at 33^a to the cam 28. In the mid-position of the handle as shown in the drawings, the inner end of the latch engages a notch on a fixed part 33^b extending upwardly from the plate 1. Thus when the finger piece is pushed downwardly the latch is disengaged from its notch and the handle and cam may be turned sidewise in either direction on the stud 29.

In closing the switch, the handle is released from its mid-position by depressing the finger piece 31 and the cam is first turned to the left with reference to Fig. 1, the inclined face of the left-hand portion of the cam then engaging the roller 27 of the bar 17^a and results in straightening the toggle 12 and closing the bridging contacts 8, giving circuit connections corresponding to closing the circuit between the middle and upper contacts of Fig. 5, thus cutting in the three phase motor 34 on partial voltage through the compensator 35. A movement of the handle and cam is then made in the reverse direction and the bridging contacts 8^a are thereby shifted into engagement as above described, giving circuit connections corresponding to closing the circuit between the middle and the lower set of contacts of Fig. 5, which connects the motor directly to the supply line.

In the particular application herein illustrated for starting induction motors, it is not desirable to provide an automatic trip for the toggle 12 in order that the great rush of starting current which is from three to four times normal full load, when the motor is started, may not open the switch, but in cases where it is desirable to trip both sides, the bar 17^a may be made full length and co-operate with a trip coil the same as shown in the case of bar 17. When the bar 17 is automatically tripped, it will be understood that the bar is raised turning upon its pivoted end at the front part of the switch, and this action results in the inclined wall 19 forcing the pin 16 of toggle 12^a toward the front of the switch thereby permitting

the toggle to collapse and the switch to automatically open by gravity action as well as by reason of the force exerted by spring 15^a. In this tripping action the underside of the bar 17 is so shaped that the pin 16 may quickly pass out of the recess 20 permitting the switch to be quickly opened. It is also apparent that in closing the contacts 8^a when the operator holds the cam against the roller 27, if an overload occurs so as to trip the bar 17, the toggle will be collapsed and the switch contacts permitted to fly open even though the operator continues to hold the cam 28 against the roller 27. In again closing the switch, the cam will be moved to mid-position and the bar 17 moved toward the front of the switch, so that the recess 20 will again engage pin 16, after which the cam may be turned so as to again close the switch. It will also be understood that in the form of the switch illustrated either of the toggles 12, 12^a may be collapsed by manually raising the corresponding bar 17^a or 17, since each of these bars has a recess 20 with sloping wall 19.

It will be understood that my invention may be embodied in various modifications without departing from the scope of the invention.

Having thus described my invention, what I declare as new and desire to secure by Letters Patent of the United States:—

1. An electric switch comprising a plurality of movable contacts, an operating toggle for each, a bar in operative relation to each toggle respectively for cramping the toggles, means for moving one of said bars to unlatch it and release the corresponding toggle, means for latching one of said bars to one of said toggles, and a rotary cam between the bars provided with a single operating means, said cam engaging each of said bars successively for successively closing the movable contacts by movement of the cam in different directions.

2. A double throw switch, comprising a plurality of toggles and movable contacts operated thereby, a pivoted cam, operating elements for the toggles, the cam being mounted in operative relation to each of said elements for moving them successively for moving the contacts in closed position by different directions of movement of said cam, means for normally latching one of said elements to one of said toggles, and means whereby one of said elements may be moved for opening its switch contacts.

3. A double throw switch having two movable contacts, operating toggles for moving said contacts respectively, operating elements for said toggles, means for detachably latching one of said elements to one of said toggles, a rotary cam for moving each of said elements successively and thereby successively cramping the toggles for

successively moving said movable contacts by different directions of movement of the cam, a handle for the cam, a manually operated latch for locking the cam in an intermediate position, and means whereby said elements may be moved for releasing the contacts.

4. An electric switch having a plurality of movable contacts, a plurality of toggles for said contacts mounted side by side, and a cam in operative relation to said toggles for successively moving said contacts by different directions of movement of said cam.

15 5. An electric switch having a plurality of movable contacts, a plurality of toggles in operative engagement with said contacts respectively, and a cam mounted to move at right angles to the direction of movement 20 of said toggles and successively engage said toggles and thereby successively move said contacts by different directions of movement of said cam.

6. An electric switch comprising a plurality of movable contacts, a plurality of operating toggles for said contacts respectively, a plurality of operating elements for said toggles, and a rotary cam for moving each of said toggles successively by movement of said element in different directions.

7. An electric switch comprising a plurality of movable contacts, operating toggles for said contacts respectively, bars normally in engagement with said toggles respectively, means on one of said bars for detachably latching said bar to one of said toggles, means adapted to engage said bars successively for successively operating said toggles, and a single handle whereby said means may be moved to successively engage said bars.

8. An electric switch comprising a plurality of movable contacts, operating toggles therefor respectively, an element in 45 latching relationship to one of said toggles,

another element in operative relationship to another toggle, a single operating member for moving said elements successively for causing the closure of said contacts successively, and electro-magnetic means for 50 moving said first mentioned element out of latching relationship to its corresponding toggle and thereby releasing said toggle.

9. An automatic switch comprising a plurality of movable contacts, operating toggles therefor respectively, a plurality of elements in operating relationship with said toggles respectively and one at least in latching relationship with its toggle, a single operating means for successively engaging 55 said elements for successively closing the switch contacts by forcing the toggles to overset position, and means for moving said element in latching relationship to its toggle in a direction to shift its corresponding 60 toggle from overset position for causing the opening of its corresponding movable contact.

10. An automatic switch comprising a plurality of movable contacts, operating 70 toggles therefor respectively, a plurality of actuating elements for said toggles respectively, one of said elements being in latching relationship to its toggle, a single operating means for successively engaging said elements for successively closing the switch contacts by forcing the toggles to overset 75 position, and means for moving at least one of said elements in a direction to unlatch said element from latching relationship to 80 its corresponding toggle and to simultaneously move the toggle from its overset position for collapsing the toggle and thereby opening its corresponding movable contact.

In testimony whereof I affix my signature 85 in presence of two witnesses.
